UNITED STATES PATENT OFFICE.

HARVEY FELDMEIER, OF LITTLEFALLS, NEW YORK, ASSIGNOR TO D. H. BURRELL & COMPANY, OF LITTLEFALLS, NEW YORK.

DRIVING MECHANISM FOR CENTRIFUGAL MACHINES.

SPECIFICATION forming part of Letters Patent No. 725,832, dated April 21, 1903.

Application filed August 25, 1902. Serial No. 120,916. (No model.)

To all whom it may concern:

Be it known that I, HARVEY FELDMEIER, a citizen of the United States, and a resident of Littlefalls, in the county of Herkimer and State of New York, have invented a new and useful Improvement in Driving Mechanism for Centrifugal Machines, of which the following is a specification.

This invention relates to the driving mechanism of that class of centrifugal machines which are operated by hand—for instance, centrifugal milk-testing machines embodying a rotary head which is secured to the upper end of the spindle and which carries the holders for the test-bottles.

The object of the invention is to provide a frame of exceedingly simple and inexpensive construction which serves as the casing in which the driving mechanism is mounted and inclosed and as means for securing the machine on a table or other support.

In the accompanying drawings, Figure 1 is a sectional elevation of a machine embodying the invention in line 11, Fig. 2, one of the bottle-holders being broken away to show the frame. Fig. 2 is a sectional rear elevation of the machine in line 22, Fig. 1, the rear portion of the gear-casing being removed. Fig. 3 is a horizontal section in line 33, Fig. 1, part of the frame being broken away. Fig. 4 is a perspective view of the rear portion of the gear-casing detached.

Like letters of reference refer to like parts in the several figures.

A represents the holders in which the test-bottles are supported and which are of any suitable construction and pivotally supported in any preferred manner to swing vertically on the rotary head B. The latter is secured, preferably detachably, to the upper end of the vertical spindle C. The spindle is journaled in bearings in the frame, which is constructed as follows:

D represents the front part of the frame, which is formed in one integral piece or casting and is composed of an upright semicylindrical hollow standard portion d and a lower portion d', which is enlarged and projects to one side of the standard and is hollow to form the front part of the inclosing casing for the drive-gearing for the spindle.

E represents the rear portion of the frame, which is composed of a complementary upright semicylindrical hollow standard portion e and a lower hollow casing portion e'. 55

The front and rear frame parts D and E are secured together to form the hollow standard and casing for the drive-gearing by suitable means, such as screws which pass through holes in the rear frame part E and are 60 screwed into screw-threaded holes e' in the front frame part D.

The spindle C and the drive-gearing for rotating the same are mounted on the front frame part D. The front standard portion d 65 extends above the complementary rear portion e and its upper end f, which overhangs the standard portion e, constitutes an upper bearing for the spindle. The spindle passes through this bearing and is journaled at its 70 lower end in a step-bearing f', formed on the lower portion of the front frame part D. The spindle is detachably retained in its bearings by suitable means, such as a collar g, attached to the spindle below the upper bearing by a pin or other means. 75

H represents the hand-actuated horizontal operating-shaft for the spindle. This shaft is journaled in a bearing h, which projects forwardly from the portion d' of the front 80 frame part D and has secured to its outer end an operating-crank h' or the like, provided with a handle h''. The inner end of the crank-shaft is connected to the spindle to rapidly rotate the same by any suitable gearing—for 85 instance, a worm-wheel I on the shaft and a worm I' on the spindle. This gearing is located in and protected by the casing d' e'.

The rear frame part E is provided with means for clamping the machine on a table 90 or other support while it is being used. For this purpose the frame part E is provided with one or more, preferably two, horizontally-projecting bearing-lugs j, adapted to rest on the table or other support, a horizontal lug j', arranged beneath the lugs j and adapted to extend under the table, and a thumb-screw J, working in a threaded hole in the lower lug j' and adapted to bear against the under side of the table or support. 95 100

I claim as my invention—

1. The combination of a rotary upright

- spindle, a horizontal driving-shaft, gearing connecting said shaft and spindle, and a two-part frame and casing consisting of separable front and rear portions, the front portion of the frame being provided with bearings in which the shaft and spindle are journaled and the rear portion being provided with means for attaching the frame to a support, substantially as set forth.
- 10 2. The combination of a rotary upright spindle, a horizontal driving-shaft, gearing connecting said shaft and spindle, and a two-part frame and casing consisting of separable front and rear portions, each having a lower casing portion inclosing said gearing, and an upwardly-projecting standard portion inclosing said spindle, one of the standard portions extending above the other and provided above the other with a spindle-bearing, substantially as set forth.
- 15 3. The combination of a rotary upright spindle, a horizontal driving-shaft arranged on one side of the spindle, and a two-part frame and casing consisting of separable front and rear portions, each having an upwardly-extending standard portion inclosing the spindle and a laterally-projecting lower casing portion inclosing the gearing, the front portion being provided with bearings in which the shaft and spindle are journaled and the rear portion being provided with means for attaching the frame to a support, substantially as set forth. 25 30

Witness my hand this 15th day of August, 1902.

HARVEY FELDMEIER.
